UNITED STATES PATENT OFFICE.

HARLOW F. GRANDY, OF CONVERSE, INDIANA.

DESIGN FOR A TOWEL-SUPPORT.

47,880.

Specification for Design.

Patented Sept. 28, 1915.

Application filed May 4, 1915. Serial No. 25,854. Term of patent 14 years.

To all whom it may concern:

Be it known that I, HARLOW F. GRANDY, a citizen of the United States, residing at Converse, in the county of Miami and State of Indiana, have invented a new, original, and ornamental Design for Towel-Supports, of which the following is a specification, reference being had to the accompanying drawing, forming a part thereof.

The figure is a perspective view of a towel support, showing my new design.

I claim:

The ornamental design for a towel support, as shown.

HARLOW F. GRANDY.

Witnesses:

A. C. ANTRIM,
B. A. SMITH.
